SPINNING OR TWISTING SPINDLE

William O. Aldrich, Whitinsville, Mass., assignor
to Whitin Machine Works, Whitinsville, Mass.,
a corporation of Massachusetts

Application May 24, 1934, Serial No. 727,309

3 Claims. (Cl. 308—152)

This invention relates to spindles used in spinning or twisting frames. Conditions of operation for such spindles have become very severe, due to the demand for increased speed and increased 5 length of bobbin, and also to the use of lower grade bobbins which are less accurately checked for straightness and balance. Each of these changes in operating conditions has increased the effect of any unbalanced load and has correspondingly increased the tendency of spindles to 10 run off-center and to chatter or vibrate at high speed.

It is the general object of my invention to provide an improved spindle construction embodying 15 multiple friction discs effective to coat with the spindle base to reduce or dampen vibration and to cause the spindle to run smoothly and without loss of power at any reasonable speed.

My invention further relates to arrangements 20 and combinations of parts which will be herein-after described and more particularly pointed out in the appended claims.

A preferred form of the invention is shown in the drawing, in which

25 Fig. 1 is a sectional side elevation of my improved spindle;

Fig. 2 is a side elevation of the bolster and parts associated therewith;

Fig. 3 is a plan view of a locking ring;

30 Fig. 4 is an enlarged sectional elevation of the lower portion of the spindle base and associated parts;

Figs. 5 and 6 are sectional plan views, taken along the lines 5—5 and 6—6 in Fig. 4 respectively, and

Fig. 7 is a partial side elevation of an alternative arrangement.

Referring to the drawing, I have shown my invention embodied in a spindle having a spindle 40 base or bolster case 10 adapted to be secured in a spindle rail 11 by the usual binding nut 12.

A spindle blade 14 is provided with the usual driving whirl 15 and is rotatably mounted in bearings in a tube or bolster 16. The spindle base 10 45 is provided with a cylindrical opening 18 to receive the bolster 16, and is also provided with an upwardly projecting boss 19 (Fig. 1) forming a step for the bottom of the bolster.

The upper end of the bolster is enlarged as 50 indicated at 20, and this portion of the bolster is a loose sliding fit in the upper end of the recess 18. A key 21 in the portion 20 is received in a keyway or longitudinally extending groove 22 (Fig. 1) in the side wall of the upper end of the recess 18.

55 The blade 14 has the usual straight running

bearing in the upper portion of the bolster 16 and also has a tapered step bearing in the bolster at its extreme lower end.

The lower portion 24 of the bolster is of substantially less diameter than the recess 18 and is provided with a plurality of friction discs 30 and with a plurality of rings 31, the discs and rings being alternately disposed.

The friction discs 30 are of such dimensions that they have slight clearance in the recess 18 10 but have substantial clearance with respect to the portion 24 of the bolster 16, as clearly shown in Fig. 6. The rings 31 on the other hand have slight clearance on the portion 24 of the bolster 15 but have substantial clearance in the recess 18 15 of the spindle base 10, as clearly shown in Fig. 5.

The rings and discs are retained on the bolster by means of a locking collar 35 having a conical inner surface adapted to coat with a locking ring 36 which may be snapped into a circular groove 20 37 (Fig. 4) formed in the lower end portion of the bolster.

A coil spring 40 encircles the portion 24 of the bolster above the discs 30 and rings 31, and the upper end of the spring 24 engages the enlarged 25 upper end portion 20 of the bolster 16, while the lower end of the spring engages the upper ring 31.

In assembling the parts, the spring, rings, discs and collar are placed on the bolster and are forced upward to a point which permits the locking ring 30 36 to be snapped into the groove 37 on the bolster.

When the parts are released, the collar 35 is forced downward over the ring 36 to a position of rest and all parts are thus securely retained in the desired assembled relation. The spring 40 35 is of such dimensions that substantial axial pressure is applied to the rings 31 and friction discs 30.

When a spindle thus constructed is placed in operation with an unbalanced load, it is found that the multiplicity of friction discs 30 exert a strong dampening effect which reduces vibration or chatter of the spindle while at the same time permitting the spindle to pivot in the usual manner about the enlarged portion 20 at the 45 upper end of the bolster and to select its own running position.

By the use of a plurality of friction discs and a plurality of rings, it has been found that long bobbins, even if inaccurately balanced, can be 50 run satisfactorily at substantially higher speeds than has been heretofore possible.

In Fig. 7 I have shown an alternative arrangement in which the discs and rings are separately grouped. This arrangement provides less rela- 55

tively movable contacting surfaces and thereby reduces the dampening effect which may be desired with only slightly unbalanced bobbins.

Having thus described my invention and the advantages thereof, I do not wish to be limited to the details herein disclosed, otherwise than as set forth in the claims, but what I claim is:—

1. A spindle comprising a recessed spindle base, a spindle blade, a bolster for said blade, means to hold said bolster from rotation in said base, said bolster having relatively slight clearance in the recess of said base at its upper end and being substantially reduced at its lower end, a plurality of friction discs slidably mounted on the reduced lower end portion of said bolster and having slight clearance with respect to the recessed spindle base but substantial clearance with respect to the bolster, a plurality of spacing rings alternating with said discs on said bolster and having slight clearance with respect to said bolster and substantial clearance with respect to said recessed base, a collar secured in fixed axial position on the lower end of said bolster and below said discs and rings, means to hold said collar in fixed position on said bolster, and a coil spring mounted on the upper part of the reduced portion of said bolster and having its upper end engaging a shoulder formed on the upper end of said bolster and having its lower end engaging the uppermost of said discs and rings at the lower end of said bolster, said spring being effective to force said discs and rings axially downward into close frictional contact with each other and against said collar, and said rings being collectively movable against friction with said bolster transversely relative to said discs and said spindle base by an unbalanced force applied to said spindle blade.
2. In a spinning machine, a tubular member, means at the lower end of said tubular member

providing a bearing which is movable relative to said tubular member, a blade having its lower end within said tubular member and rotatably supported on said bearing means, centralizing guiding means comprising a plurality of relatively movable superposed rings surrounding said means, the outer peripheries of alternating rings engaging the inner wall of said tubular member and their inner peripheries being spaced from said means, the inner peripheries of the other rings closely fitting about said means and their outer peripheries being spaced from the inner wall of said tubular member, a fixed abutment interposed between the ends of said tubular member, and a coiled compression spring acting against said abutment and said rings, said spring being operative yieldingly to restrain movement of said bearing means relative to said tubular member.

3. In a spinning machine, a tubular member, a blade having its lower end disposed within said tubular member, a floating bearing support for the lower end of said blade, and means for centralizing and yieldingly restraining movement of said bearing support relative to said tubular member, said means comprising a plurality of relatively movable superposed rings surrounding said support, the outer peripheries of alternate rings engaging the inner wall of said tubular member and their inner peripheries being spaced from said means, the inner peripheries of the other rings closely fitting about said means and their outer peripheries being spaced from the inner wall of said tubular member, a fixed abutment interposed between the ends of said tubular member, and a coiled compression spring acting against said abutment and said rings, said spring being operative yieldingly to restrain movement of said bearing means relative to said tubular member.

WILLIAM O. ALDRICH. 40
